(57) **CLAIM**

We claim the ornamental design for a shower rod bracket, as shown and described.

DESCRIPTION

FIG. 1 is a perspective view of a shower rod bracket embodying the present invention.

FIG. 2 is a front view of the shower rod bracket shown in FIG. 1.

FIG. 3 is a left side view of the shower rod bracket shown in FIG. 1.

FIG. 4 is a right side view of the shower rod bracket shown in FIG. 1.

FIG. 5 is a top view of the shower rod bracket shown in FIG. 1; and,

FIG. 6 is a bottom view of the shower rod bracket shown in FIG. 1.

The broken lines immediately adjacent the shaded areas represent the bounds of the claim and all other broken lines are for illustrative purposes only. None of the broken lines form part of the claimed design.
